UNITED STATES PATENT OFFICE.

ROBERT J. BEATTY, OF STEUBENVILLE, OHIO.

DESIGN FOR GLASS TUMBLERS, MUGS, &c.

SPECIFICATION forming part of Design No. 11,653, dated February 17, 1880.

Application filed January 20, 1880. Term of patent 3½ years.

To all whom it may concern:

Be it known that I, ROBERT J. BEATTY, a citizen of the United States, residing at Steubenville, in the county of Jefferson and State of Ohio, have invented and produced a new and original Design for Glass Tumblers, Mugs, and other Glass Vessels; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In the drawings, Figure 1 is a view of the bottom, and Figs. 2 and 3 are elevations taken from opposite sides of a glass vessel formed to illustrate the design.

In Fig. 1 I have dotted the vessel in perspective, to represent it more fully in all its features.

The tumbler or glass vessel A has its bottom end pressed in in the ordinary manner, so as to form the projecting circular rim B, on which it rests. Centrally within the space on the bottom, inclosed by the rim B, there is formed the horseshoe C, and surrounding the horseshoe is the wreath D. The horseshoe is represented as suspended to the wreath by the loops E E. On the wings of the horseshoe the words "Good Luck" are formed, and the letters are so arranged that they will be read in their proper order by the person who looks into the mouth of the tumbler or vessel.

35 In the manufacture of this design the words "Good Luck" are imprinted in raised or depressed letters, as may be preferred.

On the sides of the mug or tumbler there is formed a large central figure, representing an open four-lobe seed-pod, supported on a stem growing out of a sward covered with grass

and small flowering plants, and at the outer ends of the sward are shrubs grown to the full height, or slightly higher than the central plant.

Having thus described my invention, what I claim, and desire to secure by Letters Patent, is—

1. The design for tumbler or other glass vessel herein shown and described, consisting of the horseshoe C, formed centrally on the bottom and in the depressed area contained within the rim B.

2. The design for a tumbler or other glass vessel herein shown and described, consisting of the horseshoe C, formed centrally on the bottom and in the depressed area within the rim B, the wreath D, surrounding the horseshoe, and the loops E E, suspending the horseshoe to the wreath.

3. The design for a tumbler or other glass vessel herein shown and described, consisting of the horseshoe C, formed centrally on the bottom, and the words "Good Luck" imprinted in raised or depressed letters, as may be preferred, on the arms or wings of the horseshoe.

4. The design for a tumbler or mug herein shown and described, consisting of the central four-leaf open seed-pod formed on the side, supported on a stem growing out of a sward covered by grass and flowers, and flanked by shrubs of same or about the same height as the said seed-pod and stem.

In testimony that I claim the foregoing as my own I have hereunto set my hand this 17th day of January, 1880.

R. J. BEATTY.
